UNITED STATES PATENT OFFICE.

PARK A. HERR, OF HILLSIDE, NEW JERSEY, ASSIGNOR TO THE SINGER MANUFACTURING COMPANY, A CORPORATION OF NEW JERSEY.

LOOP-TAKER-ACTUATING MECHANISM FOR SEWING-MACHINES.

1,396,040.

Specification of Letters Patent.

Patented Nov. 8, 1921.

Application filed September 30, 1919. Serial No. 327,377.

To all whom it may concern:

Be it known that I, PARK A. HERR, a citizen of the United States, residing at Hillside, in the county of Union and State 5 of New Jersey, have invented certain new and useful Improvements in Loop-Taker-Actuating Mechanisms for Sewing-Machines, of which the following is a specification, reference being had therein to the accompanying drawings.

This invention relates to sewing machines of the type employing oscillating loop-takers and more particularly to the mechanism for imparting to the loop-taker its 15 oscillatory movements.

The invention has for an object to increase the speed of the machine by reducing the extent of oscillation of the shuttle or other loop-taking element and still retain 20 the proper timing of the respective parts.

A further object of the invention is to provide a loop-taker actuating mechanism adapted to impart a variable motion to the loop-taker shaft whereby the loop-taker is 25 given a retarded motion or dwell at a certain stage of its oscillation permitting the needle-eye to rise above the work before substantial distention of the needle-thread loop begins, thereby greatly reducing the friction 30 on the thread during such distention.

According to the present invention the objects are attained in a shuttle-actuating mechanism comprising a main-shaft provided with a crank to which is connected 35 one end of a two-part pitman comprising a short upper section and a comparatively long lower section. This pitman is reciprocated by said crank and is at its lower end suitably connected to oscillate the loop-taker shaft. The upper or short section of 40 the pitman is pivoted to turn about an axis located comparatively near the main-shaft and, due to the relation of the arcs in which the crank and the upper section 45 of the pitman move, the reciprocatory motion of the pitman is retarded and accelerated at different stages, thereby correspondingly affecting the movements of the shuttle, as will later be explained.

By the employment of the present mechanism it becomes possible to use a short-beak shuttle or other loop-taker and to still allow the needle-eye to rise above the work before substantial distention of the needle-thread 55 loop begins.

Heretofore, in order to obtain this condition, it has been customary to employ a shuttle having a beak substantially longer than is used with the present mechanism, which necessitated a correspondingly greater 60 oscillation of the shuttle to position the point thereof in rear of the needle preparatory to taking the thread-loop, and by eliminating this excessive oscillation it is practicable to run the machine at a substan- 65 tially increased speed.

The invention is shown in its preferred form in the accompanying drawings, in which Figure 1 is a side view partly in section of a sewing machine embodying the present invention. Fig. 2 is a front end elevation thereof. Fig. 3 is a sectional view taken on the line 3—3 of Fig. 1. Fig. 4 is a detail bottom view showing the mechanism for converting the reciprocatory motion of the pitman into oscillatory motion of the loop-taker driving shaft and Figs. 5, 6 and 7 are detail views, in different positions, of the shuttle oscillating mechanism and also showing the relation of the shuttle 80 to its actuating mechanism and to the needle.

Referring more particularly to the drawings, the machine is constructed with a base 1, standard 2 and overhanging arm 3 terminating in the head 4. Journalized within 85 the arm 3 is a main or needle-bar driving shaft 5 carrying at its rear end a belt- and hand-wheel 6 and having secured at its front end a disk 7 which carries a crank-pin 8 connected by a link 9 to a block 10 90 secured upon the needle-bar 11, whereby reciprocatory motion is given to the needle-bar and to the needle 12 secured therein and which carries the needle-thread *t*. A spring-depressed presser-bar 13 is slidingly mounted 95 in the head 4 and carries at its lower end the presser-foot 14. A throat-plate *p*, adapted to support the work *w* being acted upon, is located beneath the presser-foot and is supported by the machine base. 100

Thread take-up mechanism 15 is also carried by the head 4 and actuated from the disk 7. Feeding mechanism, designated generally as 16, is provided and acts to feed the material between successive stitches. 105

Coöperating with the needle 12, in the formation of stitches, is the shuttle 17 formed with a loop-seizing beak 18 and supporting the bobbin-case 19 adapted to carry the bobbin 20 upon which is wound the bob- 110

bin thread 21. The shuttle 17 is fitted to oscillate within the shuttle-race 22 and is actuated by a shuttle-driver 23 secured upon the shuttle-shaft 24 journaled in bearings 25 carried by the machine base 1.

Oscillatory movements are imparted to the shaft 24 by a loop-taker actuating element preferably comprising a crank 26 on the main-shaft 5 and a two-part pitman *d* comprising an upper or shorter section 27 pivotally connected to a lower or longer section 28 by a screw 29. In the present embodiment of the improvement the lengths of the sections 27 and 28 are about as one-to-four and the section 27 is about two-and-one-half times the length of the actuating crank to which it is directly connected. The pitman *d* has, at its upper end, a strap embracing the crank 26 and at its lower end is pivotally connected to a motion-converting and multiplying mechanism comprising a crank- or rock-arm 30 fixed upon the short rock-shaft 31 journaled in bearings 32 carried by the machine base 1 and a second rock-arm 33 which is connected by a link 34 to a crank- or rock-arm 35 carried by the rear end of the loop-taker shaft 24.

A radius-arm 36, adapted to control the path of movement of the pitman is connected at one end to the pivot-screw 29 and has its other end fulcrumed upon a bracket 37 forming a part of the machine standard.

Referring to Fig. 6, it will be observed that, as the short section of the pitman is pivoted to turn about an axis located comparatively near the main-shaft, an arc *a*, swung from said axis, approximates the arc *b* in which the crank turns when approaching and leaving its uppermost position.

The arc *c* is swung from a point *x* disposed eccentrically to the rock-shaft 31 where driving connections, as heretofore used, comprising a single element, have been pivoted. It will be understood that the more nearly an arc swung from the pivot-point of the upper section of the pitman approximates the path of movement of the crank the lesser will be the reciprocatory movement of said pitman, and consequently the shuttle movement, at that time, will be retarded.

As the crank is passing its lowermost position it turns in an arc *f* oppositely disposed to an arc *e* swung from the axis of the short pitman-section, which at that time is in its lowermost position as is also the radius arm 36 of which the center line is represented by the dot-dash line 36^x, causing an increased endwise movement of the pitman and a corresponding acceleration of the shuttle movement, equal in amount to its previous retardation, thereby keeping the several parts in proper time for the formation of the succeeding stitch. In one aspect of the present improvement, the link-element 28 is connected, not directly with its actuating ele-

ment 26 as in prior well known constructions, but indirectly therewith through a motion-retarding device comprising a link-element 27 with its controlling radius arm 36.

It is obvious that the present shuttle mechanism is adaptable to sewing machines which vary greatly in the height of the standard, it being necessary only to substitute a longer or a shorter lower section in the pitman *d* in order to maintain a corresponding timing, a very desirable feature not found in machines having a one-piece pitman.

Having thus set forth the nature of the invention, what I claim herein is—

1. In a sewing machine, the combination with an overhanging arm, a driving shaft supported thereby, a crank carried by said shaft, an oscillating shaft, and stitch-forming mechanism comprising a needle and a loop-taper adapted to take a loop of thread from the needle and distend the loop, of means connected with the said oscillating shaft for actuating said loop-taker whereby the movement thereof is retarded at a predetermined time to permit the needle to rise above the work before substantial distension of the loop begins, said means including a two-part pitman composed of pivotally connected sections of which one is connected to the crank on the main-shaft and the other to a motion converting mechanism linked to an arm carried by said oscillating shaft.

2. A loop-taker actuating mechanism for sewing machines comprising a main-shaft, a crank carried thereby, a loop-taker shaft provided with a rock-arm, a rock-shaft, a rock-arm carried thereby, a link connecting said rock-arms, and a pitman, comprising sections pivotally connected together, and connected to said crank and controlled to actuate said rock-shaft.

3. A loop-taker actuating mechanism for sewing machines comprising a main-shaft, a crank carried thereby, a loop-taker shaft provided with a rock-arm, a rock-shaft, a rock-arm carried thereby, a link connecting said rock-arms, and a two-part pitman controlled to actuate said rock-shaft and comprising relatively short and long sections pivotally connected together and connected respectively to the crank and to an arm on the rock-shaft.

4. A loop-taker actuating mechanism for sewing machines comprising a main-shaft, a crank thereon, a loop-taker shaft provided with a rock-arm, a rock-shaft, a rock-arm thereon, a link connecting said rock-arms, and a two-part pitman controlled to actuate said rock-shaft and comprising a relatively short section connected to said crank and a relative long section pivoted at one end to said short section and eccentrically connected at its other end to said rock-shaft.

5. A loop-taker actuating mechanism for sewing machines comprising a main-shaft, a crank thereon, a loop-taker shaft provided with a rock-arm, a rock-shaft, a rock-arm carried thereby, a link connecting said rock-arms, a pitman, comprising two pivotally connected sections, of which one is connected to said crank and the other is connected to said rock-shaft, and means for controlling the direction of movement of the component sections of said pitman. 40
6. A loop-taker actuating mechanism comprising a main-shaft, a crank thereon, a rock-shaft, a crank thereon, a pitman connection between said cranks composed of two pivotally connected sections of unequal length of which the shorter is pivotally connected to the main-shaft crank and the longer is connected to the rock-shaft crank, and means for controlling the path of movement of the pivotal connection between the pitman sections. 50
7. A loop-taker actuating mechanism comprising a main-shaft, a crank thereon, a rock-shaft, a crank thereon, and a dwell-producing driving connection between said cranks and including a two-part pitman with pivotally connected component sections of different length of which the shorter is directly connected with the main-shaft crank. 55
8. A loop-taker actuating mechanism comprising a main-shaft, a crank carried thereby, a loop-taker shaft provided with a rock-arm, a rock-shaft, a rock-arm carried thereby, a link connecting said rock-arms, a pitman comprising pivotally connected sections 35
- embracing said crank and adapted to actuate said rock-shaft, and means for controlling the movement of said pitman, said means including a radius-arm pivotally connected at one end to said pitman and fulcrumed at its other end upon a fixed support. 45
9. A loop-taker actuating mechanism for sewing machines, comprising a main-shaft, a crank thereon, a loop-taker shaft provided with a rock-arm, a rock-shaft, a rock-arm carried thereby, a link connecting said rock-arms, and a pitman composed of a plurality of pivoted sections connected at one end to the crank on the main-shaft and eccentrically connected at its opposite end to the rock-shaft, whereby one end of one of said sections is moved in a circular path defined by said crank and the other end acting through another of said sections transmits variable oscillatory motions to the shuttle-shaft. 55
10. A loop-taker actuating mechanism for sewing machines, comprising a rotary shaft provided with a loop-taker actuating element, a loop-taker driving shaft, a loop-taker operatively connected therewith, a pitman element connected with and imparting operative movements to said loop-taker driving shaft, and a driving connection including a motion-retarding device between said pitman element and said loop-taker actuating element. 60

In testimony whereof, I have signed my name to this specification. 70
